UNITED STATES PATENT OFFICE.

EMIL JACOBSEN, OF PORT WASHINGTON, NEW YORK, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed September 5, 1918, Serial No. 252,764. Renewed February 15, 1924.

To all whom it may concern:

Be it known that I, EMIL JACOBSEN, a citizen of the United States of America, and a resident of Port Washington, Nassau County, and State of New York, have invented 5 certain new and useful Improvements in Automatic Telephone Systems, of which the following is a specification.

My invention relates in general to improved circuits and apparatus for use in semi-automatic telephone systems, in which automatic switches are controlled either automatically by a subscriber, or through the medium of an operator to establish connections.

More specifically, my invention relates to 15 an improved connector switch of the type having automatic trunk selecting functions, such as is used for connecting with trunk lines extending to private branch exchanges, and being commonly known as a rotary connector. The connector shown herein may be considered as being an improvement on the connector shown in my pending application Ser. No. 174,013, filed June 11, 1917.

20 My improved connector is arranged so that the test of the first contact associated with a group of trunk lines extending to a private branch exchange determines whether or not there is an idle trunk in that group. Also 25 when this connector is used by an operator to establish a connection to such a group of trunk lines, the connector will stop on the first contact of the elected group, if all the trunks are busy, and give the operator the 30 busy signal; then, when any one of the trunks in that group become idle, the connector will operate to seize that idle trunk. This and other objects of my invention will be more 35 fully described hereinafter.

40 In the drawings comprising Figures 1 and 2, I have shown a sub-station A, a line switch C individual to the line of sub-station A, a selector switch D, accessible to the line switch C and a rotary connector switch E, accessible 45 to the selector switch D. Accessible to the connector switch E, I have shown a group of trunk lines extending to a branch exchange.

50 Referring to Figure 1, the sub-station A may be of any approved automatic type, such for example as the sub-station shown in the British patent to Martin #1419 of 1910. As 55 represented, herein, it comprises essentially, the receiver 11, transmitter 12, switchhook 13, ringer 14, and condenser 15. Being an

automatic sub-station, it is also provided with a pair of impulse springs 16 and 17, which may be controlled by an impulse wheel through the medium of a finger hole dial (not shown).

60 The line conductors 18 and 19 of the sub-station A extend to the main exchange, where they terminate in an individual line switch C. The line switch C may be of the general type of line switch shown in U. S. Letters 65 Patent #1,126,727, granted February 2, 1915, to Dietl. Through the medium of the line switch C, the line of sub-station A when calling, is given access to a plurality of trunk lines extending to selector switches.

70 One of the trunk lines to which the line switch C has access, is shown extending to the first selector switch D. The selector switch D may be of the general type of selector switch disclosed in U. S. Letters 75 Patent No. 815,321, granted March 13, 1906, to Keith, Erickson and Erickson. The side switch and private magnet are omitted, however, and the circuits are modified in accordance with the two wire system of control.

80 The first selector switch D may have access to other selector switches similar to the switch D. As herein shown however, the selector D has access to trunk lines extending to connector switches, one of the trunk lines 85 extending to the connector switch E. The connector E may be of the general type of connector switch disclosed in U. S. Letters Patent No. 815,176, granted March 13, 1906, to Keith, Erickson and Erickson. The side 90 switch and private magnet are omitted and the circuits are modified in accordance with the two-wire system of control. The rotary connector E is also accessible to toll selector switches (not shown) over the conductors 95

65, 66 and 67. As before mentioned, the connector E may have access to groups of 100 trunk lines extending to private branch exchanges, also, it may be stated, that each bank level comprises ten contact sets, in which terminate ten trunk lines, which latter may be divided into any convenient number of trunk lines from one to ten in each group. Each contact set comprises four contacts, which are the usual line, private or test contacts, and an extra test contact. This extra test contact is dead except in the case of the contact sets which are associated with the first and last trunk lines of a group. The two test contacts associated with the last 110

trunk line of each group being connected together and the first extra test contact associated with each group being connected to a normally open contact, which is controlled by the bridge cut-off relay, individual to the first trunk line of each group.

One of the trunk lines accessible to the connector E is the trunk line 96 and 99, which is assumed to be the first trunk line in some particular group. Each of the trunk lines in this group are two way trunk lines. That is, the operator at the branch exchange may extend a connection to the main exchange, through the medium of an individual trunking switch, which may be similar to the switch C. I have only shown the bridge cut-off relay of the trunking switch individual to the trunk line 96 and 99, and the chain contacts associated with each bridge cut-off relay in that group, for the purpose of placing a ground potential on the first extra contact 97 in that group, when all the trunks become busy, to be more fully described hereinafter.

25 While I have shown throughout the drawings a plurality of batteries, it is to be understood that there is preferably but one battery having its positive pole grounded, or rather there may be one battery in the main exchange and a separate battery in each of the branch exchanges. Associated with the connector E, I have shown a ringing equipment H, and a busy signalling machine I. This apparatus may be the usual type, such as is found in well known telephone systems.

Having briefly described the apparatus involved, I will now proceed to explain more in detail the operation of the same.

40 When the subscriber at sub-station A removes his receiver, a circuit is closed at the switch-hook springs for the line relay 20 of the switch C in series with the line circuit. Relay 20 upon energizing, closes a circuit at springs 21, including switching relay 22, and rotary magnet 23 in series, and at the same time at springs 24 for the magnet 23 to the private wiper 27. Suppose that the trunk line upon which the switch C is resting is busy; then a ground potential is present on the private contact corresponding to this trunk; this ground potential will short the high resistance relay 22 and energize the rotary magnet 23 to step the wipers 26, 27 and 28 to the contacts of the next trunk line. If this trunk line is busy, the rotary magnet will again be energized and this operation will continue until an idle trunk is reached, at which time there will be no potential present at the contact which the private wiper 27 meets. Relay 22 will no longer be shorted out and will immediately energize over the series circuit hereinbefore traced, to extend the line of sub-station A to a trunk line leading to a selector switch.

Suppose the first idle trunk is the trunk line 29, 30 and 31 leading to the selector switch D. Relay 22 upon energizing closes a circuit for the line relay 34 of switch D in series with the line circuit and wipers 26 and 28. Relay 34 upon energizing, closes a circuit at springs 35 and 36 for slow release relay 38. Relay 38 energizes to prepare a circuit at springs 39 and 40 for slow relay 42 and vertical magnet 43 in series, opens a point at springs 40 and 41 in the circuit of release magnet 44, and closes a circuit at springs 45 to hold the relay 22 of switch C energized. When a series of impulses corresponding to the first digit of the called number are delivered by the calling device at sub-station A, the relay 34 operates to open and close the circuit of the vertical magnet 43 at springs 36 and 37, a corresponding number of times, to thereby step the wipers 51, 52 and 53 to a desired level of bank contacts. Relay 42 is energized in series with magnet 43, and operates to close a circuit at springs 47 and 48 for the rotary interruptor relay 49. Relay 49 energizes to prepare a circuit for the rotary magnet 50 at springs 55, and close a locking circuit for itself, through springs 54. As soon as relay 42 de-energizes after the impulses cease, a circuit for the rotary magnet is closed at springs 46 and 48. The magnet 50, therefore, operates to rotate the wipers 51, 52 and 53 onto the first contact of the elected level and opens the locking circuit of relay 49 at springs 56. Relay 49 then de-energizes and opens the circuit of magnet 50 at springs 55, which magnet de-energizes and prepares a new circuit for relay 49 to the private wiper 52. If the first trunk is busy, the relay 49 will again be energized by the guarding potential at the contact associated with wiper 52 to again close the circuit of magnet 50. The rotary magnet again operates to step the wipers to the next trunk line. When the first idle trunk is reached, no potential is present at wiper 52, and relay 57 which has heretofore been short-circuited, is energized in series with relay 49 from ground potential at springs 45. Relay 49 being of lower resistance than 57, does not energize at this time. Relay 57 upon energizing, prepares a locking circuit for itself at springs 58, which will be completed over wiper 52 from the next succeeding switch, also by means of springs 60 and 61, extends the line circuit to a trunk line leading to a connector switch.

Suppose the first idle trunk line is the trunk line 62, 63 and 64 leading to the rotary connector switch E. Then a circuit for line relay 70 is completed as follows: from ground through lower winding of relay 70, springs 71 and 74, conductor 64, wiper 53, springs 61, conductor 31, wiper 28, to and through sub-station A, wiper 26, conductor 130

29, springs 60, wiper 51, conductor 62, springs 77 and 75, upper winding of relay 70 to battery. Relay 70 upon energizing, closes a circuit for slow release relay 79. 5 Relay 79 upon energizing, places ground potential through springs 80 to the release trunk to render the switch E "busy" to other calls and to hold relays 22 and 57 of switches C and D respectively, energized, 10 opens a point in the circuit of release magnet 81 at springs 83 and 82 and prepares a circuit for relay 85 and vertical magnet 86 in series at springs 83 and 84.

Assume that the subscriber at sub-station 15 A desires to call into a branch exchange of which the first trunk is the trunk line 96 and 99. Now, when a series of impulses corresponding to the second digit of the called number is transmitted by the calling 20 device, the line relay 70 operates to open and close the circuit of magnet 86 at springs 101. The circuit of the vertical magnet 86 extends from ground through springs 101, springs 83 and 84, springs 102 and 103, slow relay 25 85 and vertical magnet to battery. The vertical magnet will be operated a number of times to step the wipers 88, 89, 90 and 91 to the group or level of trunk lines in which terminals of the desired line are located. Upon the first vertical step of the 30 wipers, the off normal springs 102 and 103 are opened and spring 102 comes into contact with spring 104. Although the circuit for the vertical magnet is opened by 35 springs 102 and 103, a new circuit has been closed by the operation of relay 85, which circuit extends from ground through springs 101, springs 83 and 84, springs 102 and 104, springs 106 and 105, and over the previously 40 traced circuit through the vertical magnet. Relay 85 remains energized during the series of impulses to the vertical magnet and upon de-energizing after the impulses cease, prepares a circuit for slow relay 108 and the 45 rotary magnet 109 in series.

Now, when the line relay 70 is again operated in response to the third or last digit of the called number, the rotary magnet is operated to rotate the wipers 88, 89, 90 and 50 91 to the terminals of the first line in the desired group. The circuit of the rotary magnet extends from ground through springs 101, springs 83 and 84, springs 102 and 104, springs 106 and 107, slow relay 108, springs 55 110, springs 111 and rotary magnet 109 to battery. Relay 108 energizes upon the first rotary impulse and retains its armature during the series of impulses to the rotary magnet 109, and at springs 112 and 113 closes a 60 circuit for relay 115. Relay 115 upon energizing, prepares a circuit at springs 120 for the lower winding of relay 119 and winding of relay 118 in series, also closes a locking circuit for itself at springs 117. Relay 108 65 upon de-energizing, after the impulses to the

rotary magnet cease, closes the circuit for lower winding of relay 119 and winding of relay 118 in series, but without effect at this time. Relay 118 is adjusted stiff and the springs 125 and 126 are to make contact before springs 127 close. If the first trunk line in the group is busy the private contact 98 will be grounded and a circuit for relay 118 will be closed from ground at contact 98, wiper 90 in engagement therewith, 70 springs 116, springs 121 and 122, springs 124, winding of relay 118 to battery. Relay 118 now energizes, closes a locking circuit for itself at contact 126, and at contact 127 closes a circuit for the rotary magnet 109 as follows: from ground at springs 80, through 75 springs 130 and 128, springs 113 and 114, springs 127, springs 110, springs 111 and through magnet 109 to battery. The rotary magnet now operates to step the wipers 88, 89, etc., to the contacts associated with the next trunk line and at springs 124 opens the circuit of interruptor relay 118; whereupon relay 118 falls back and breaks the circuit of the rotary magnet. On the deenergization of the rotary magnet, if the contact engaged by the private wiper 90 is grounded, 80 relay 118 will again be energized and the rotary magnet will then operate to step the wiper to the next succeeding contact. This 85 operation will continue until the last trunk in the group is reached and if that trunk line is busy, a ground potential will be present on both test contacts associated with that trunk, since the last two test contacts of any 90 group of trunks are connected together as hereinbefore stated. Therefore a circuit will be completed for busy relay 132 from ground at the contact associated with wiper 89 through springs 125, springs 133 and 134 95 and through relay 132 to battery. Relay 132 upon energizing, closes a locking circuit for itself at springs 134 and 135, opens a point in the circuit of rotary magnet 109 at springs 110, and connects the secondary winding 100 of busy machine I with the lower talking conductor, thereby giving the subscriber at sub-station A, a busy signal.

If all the trunks in the elected group had been busy just prior to the last series of impulses delivered by the calling device, then a ground potential would have been present at the first extra test contact 97. Under these circumstances, since the bridge cut-off relay of each trunk is energized, a circuit may be 115 traced from ground at bridge cut-off relay springs 140 associated with the last trunk line in the group, springs 141, springs 142, test contact 97, and over the previously 120 traced circuit, through the busy relay 132 to battery. Current flow over the above circuit energizes relay 132, thereby giving the subscriber a busy signal and avoiding unnecessary rotation of the connector switch E.

When the calling subscriber replaces his 125

receiver, the circuit of line relay 70 is opened at the springs operated by the receiver hook. Relay 70 de-energizing, opens the circuit of relay 79 and closes a point in the circuit of release magnet 81 at springs 101. When relay 79 de-energizes it closes the circuit of the release magnet 81 at springs 82 and 83, also removes ground potential from the release trunk at springs 80, which opens the holding circuit of relays 22 and 57 of switches C and D respectively. Relay 57 of switch D upon de-energizing, closes a circuit for the release magnet 44. The energization of magnets 44 and 81 of switches D and E respectively, restores the wipers to normal position in the well known manner.

Now when this rotary connector is seized by a toll operator over the trunk conductors 65 and 67, the line relay 70 is energized through the windings of differentially wound relay 143. The relay 143 does not energize at this time, as its two windings oppose each other. The connector switch E is operated through the medium of its line relay 70 in the same manner as hereinbefore described, to bring the wipers 88, 89, 90 and 91 into engagement with the first set of contacts associated with the selected group of trunk lines; assuming that wiper 89 is now in engagement with contact 97 and all the trunks in that group are busy, a circuit for busy relay 132 is completed as hereinbefore traced. Relay 132 upon energizing at this time closes a shunt or short circuit about the lower winding of slow relay 143 at springs 144', connects the secondary winding of the busy machine I with the lower talking conductor, opens a point in the circuit of rotary magnet 109, at springs 110 and closes a holding circuit for itself at springs 134 and 135.

The short-circuit which is thus established about the lower winding of relay 143 causes said relay whose windings are differential, to be energized, thereby switching the locking circuit of the busy relay 132 to the wiper 89. This new circuit extends from ground at wiper 89, springs 125, springs 144 and 145, springs 135 and 134, and relay 132 to battery. It will be seen, therefore, that relay 132 instead of being permanently locked, remains energized only as long as all of the trunk lines in the group are busy, and until ground is removed from the private contact 97.

Supposing that the second trunk now becomes idle, springs 141 will be separated and ground will be removed from contact 97; therefore relay 132 will deenergize and restore its springs to normal and at springs 110 closes a circuit for rotary magnet 109, as previously traced, which will operate to step the wipers onto the next set of contacts associated with the second trunk. Therefore as soon as wiper 90 comes into engagement with the idle contact associated

with the second trunk line, a circuit for lower winding of relay 119 is completed over the following path: from ground through springs 80, springs 130 and 128, springs 113 and 114, springs 146 and 144, 70 springs 135 and 136, springs 120, lower winding of relay 119, springs 121 and 122, springs 116, wiper 90 and through the bridge cut-off relay associated with the second trunk line to battery. Relay 119 is now 75 energized and closes a locking circuit for its upper winding at springs 129 and 130, and places direct ground on wiper 90 at springs 122 and 123. Another result of the energization of relay 119, is the closure of 80 springs 147 and 148, thereby connecting ringing current to the called line from the ringing apparatus H, whereby the called subscriber is signaled in the usual and well known manner. Upon the called party 85 responding, a circuit for the ring cut-off relay 148 is completed, which upon energizing, disconnects generator from the called line and closes a circuit for relay 149. Relay 149 energizes and operates the springs 90 72 and 76 and the associated contacts to reverse the connections of the line relay 70 to the calling line and to short-circuit the windings of relay 143.

The release of the connector E after conversation has taken place, is controlled in the same manner as that previously described, when a connection was established by the subscriber at sub-station A.

It will be seen therefore, that I have provided a very useful and efficient method by which an operator after establishing a connection to a group of trunks extending to a branch exchange which are all in use, will be automatically connected to the first trunk 100 line to become idle.

Having fully described and ascertained my invention in the foregoing specification, what I claim to be new and desire to have protected by Letters Patent will be pointed 110 out in the appended claims.

What I claim as my invention is:

1. In a telephone system, a calling line, an automatic switch, a group of trunk lines accessible to said switch, means for operating said switch for causing it to automatically rotate over said trunk lines in search of an idle trunk line, and means for preventing said switch from automatically rotating if all of said trunks are busy and 120 for giving the calling subscriber a busy signal either before or after said automatic rotation.

2. In a telephone system, automatic switches, groups of trunk lines accessible 125 to said switches, primary and secondary magnets for operating said switches, means for operating both primary and secondary magnets in response to digits of a called number and for causing the secondary mag- 130

- net to automatically operate to select a trunk in one of said groups, means for preventing the automatic operation of any of said switches and for giving the busy signal when 5 all of the trunks in the selected group are busy, means for causing any of said switches to automatically operate when any one of the trunks in the elected group becomes idle before said switch is released, and means for 10 again giving the busy signal should the idle trunk again become busy before the wipers of said switch gain access thereto.
3. In a telephone system, an automatic switch, a plurality of trunk lines accessible thereto divided into groups and sub-groups, means for operating said switch to select a sub-group of trunks, means controlled over either of two different paths for causing said switch to automatically rotate over the 15 trunks in said sub-group in search of an idle one, means for preventing the rotation of said switch when all the trunks in the sub-group are busy, and means effective when the switch is controlled over one path for permitting 20 the automatic rotation of said switch when any one of the trunks in said sub-group becomes idle and for preventing further operation of the switch when the same is controlled over the other path.
- 30 4. In a telephone system, a trunk selecting switch accessible via two paths, a plurality of trunk lines accessible thereto divided into groups, a test contact for each group, a test wiper for the switch, means for operating said switch to move said test wiper into engagement with the test contact of a group, means for making said group of trunks busy, means for preventing further 35 operation of said switch if all the trunks in the group are busy when the wiper meets the test contact of the group, means for permitting further operation of the switch when one of the trunk lines in the group becomes idle if said switch has been seized over one path and means for preventing further 40 operation of the switch when one of the trunk lines in the group becomes idle if the switch has been seized over another path.
5. In a telephone system, an automatic switch, groups of trunk lines accessible to said switch, means for operating said switch over one path in response to digits of a called number for causing it to automatically operate to select a trunk in one of said 45 groups, means for preventing the automatic operation of said switch and for operating a busy signal when all of the trunks in the selected group are busy, means for preventing any further operation over said path; said switch operated over other paths in response to digits of a called number, means controlled over said other paths for preventing the automatic operation of said switch when all of the trunks in the selected 50 group are busy, and means for causing said switch to automatically operate when any one of the trunks in the selected group become idle before the switch is released.
6. In a telephone system an automatic switch, groups of trunk lines accessible thereto, means for seizing said switch via more than one path and for operating the switch to cause it to automatically select an idle trunk line in one of said groups, means operated when all of the trunks in the group are busy for giving a busy signal to the calling subscriber and for preventing the operation of said automatic selecting means, and means operable only when the switch is seized via one of said paths for permitting the operation of said automatic selecting means whenever a trunk line in the group becomes idle.
7. In a telephone system, calling lines, an automatic switch, a group of trunk lines accessible to said switch, said switch having an automatic selecting operation to seize idle trunks, means in said switch when operated over one of said calling lines for transmitting a busy signal to the calling line when all the trunks are busy and for preventing any automatic selecting operation of said switch, and means in said switch effective when said switch is operated over another of said lines for transmitting a busy signal thereto when all the trunks are busy previous to or after the automatic selecting operation of the switch.
8. In a telephone system, an automatic switch, said switch accessible to groups of trunk lines, a busy signaling device in said switch, said device operable only one time when said switch is seized in one manner and operable a plurality of times when seized in another manner.
9. In a telephone system, an automatic switch having a relay therein, a group of trunks accessible to said switch, means controllable via two paths for operating said switch and for causing it to automatically rotate over said group in search of an idle trunk line, said relay being included in one of said paths only, means for preventing said switch from automatically rotating if all of said trunks are busy and for giving the calling party a busy signal, and means controlled by said relay when said switch is operated over the associated path for thereafter allowing the automatic rotation of said switch when one of said trunks become idle.
10. In a telephone system, an automatic switch, a group of trunks accessible to said switch, means controllable via two paths for operating said switch and for causing it to automatically rotate over said group in search of an idle trunk line, means for preventing said switch from automatically rotating if all of said trunks are busy and for giving the calling party a busy signal,

and a relay in said switch for determining whether or not automatic rotation will be permitted after a busy.

11. In a telephone system, an automatic switch, a group of trunk lines accessible to said switch, a trunk line incoming to said switch and having two branches over either of which said switch may be taken for use, trunk hunting mechanism in said switch, means for preventing the operation of said mechanism in case all the trunks in said group are busy, and means effective only in case said switch is taken for use via a particular one of said branches for automatically initiating the operation of said mechanism if a trunk line in said group becomes idle before the switch is released.

12. In a telephone system, a group of trunk lines, an automatic switch for use either by an operator or a calling subscriber, trunk hunting mechanism in said switch, means for preventing the operation of said mechanism in case all the trunks in said group are busy, and means effective only in case said switch is in use by an operator for automatically initiating the operation of said mechanism if one of said trunk lines becomes idle before the switch is released.

13. In a telephone system, groups of trunk lines, a rotary connector, means controllable either by an operator or a calling subscriber for operating said connector to select a group of said trunk lines, automatic mechanism for causing said connector to select an idle trunk in a selected group, means for preventing the operation of said mechanism in case all the trunks in the selected group are busy, and means effective only in case said connector is in use by an operator for automatically initiating the operation of

said mechanism in case a trunk in the selected group becomes idle before the connector is released.

14. In a connector switch, a line relay, a differential relay in series with said line relay, a test relay, and contacts controlled by said test relay for shunting one winding of said differential relay.

15. In a connector switch, a test relay, a test wiper, an initial energizing circuit for said relay including said wiper, a locking circuit for said relay excluding said wiper, a second locking circuit for said relay including said wiper, and a differential relay for determining which of said locking circuits is to be effective.

16. In a connector switch, a test relay, a test wiper, an initial energizing circuit for said relay including said wiper, a locking circuit for said relay excluding said wiper, a second locking circuit for said relay including said wiper, a line relay, and a relay in series with said line relay for determining which of said locking circuits is to be effective.

17. In a connector switch, a test relay, a test wiper, an initial energizing circuit for said relay including said wiper, a locking circuit for said relay excluding said wiper, a second locking circuit for said relay including said wiper, two incoming lines terminating in said connector for alternative use in connecting therewith, and a relay included in only one of said lines for rendering one locking circuit effective and the other ineffective.

Signed by me at Chicago, Cook County, Illinois, this 28th day of August, 1918.

EMIL JACOBSEN
